Primary Examiner — Brett Miller*Assistant Examiner* — Sara Michie Pottenger(74) *Attorney, Agent, or Firm* — Baker Donelson
Bearman Caldwell & Berkowitz, PC(57) **CLAIM**

The ornamental design for a pet door as shown and described.

DESCRIPTION

FIG. 1 is a perspective view of a pet door showing our new design.

FIG. 2 is a front view thereof.

FIG. 3 is a top view thereof, the bottom view being the same thereof.

FIG. 4 is a rear view thereof; and,

FIG. 5 is a right side view thereof, the left side being a mirror image thereof.

The broken lines depict portions of the pet door indicate unclaimed portions and form no part of the claimed design.
